UNITED STATES PATENT OFFICE.

HENRY MERLE WILLIAMSON, OF OAK PARK, ILLINOIS.

ELECTROMECHANICAL TRANSFORMING DEVICE.

Application filed July 22, 1925. Serial No. 45,432.

To all whom it may concern:

Be it known that I, HENRY MERLE WILLIAMSON, a citizen of the United States, residing at 312 Washington Blvd., Oak Park, county of Cook, State of Illinois, have invented a new and useful Improvement in an Electromechanical Transforming Device, of which the following is a specification with the appended claims.

10 This invention relates to electro-mechanical transforming devices such as are used for transforming electrical energy into mechanical and sound energy, being particularly suitable for telephonic receiving apparatus and radio loudspeaking devices.

15 The prime object of this invention is to produce a device that will give the highest efficiency in volume and quality of articulation and music, where a minimum amount of distortion is desired.

20 Another object of this invention is to neutralize mechanical and electrical periodicities such as exist in the common type of telephonic apparatus.

25 Another object of this invention is to provide for an electrical receiver with margin of clearance in its structure between stationary and moveable parts to eliminate adjustments.

30 Other objects will be apparent from the following description:

Fig. 1 shows non-magnetic spacers; Fig. 2 shows an armature and a torsional spring for mounting the armatures; Fig. 3 shows perspective of armature assembly; Fig. 4 shows perspective of the double armature and diaphragm assembly; Fig. 5 shows a schematic drawing of the apparatus; Fig. 6 shows one of the two pole pieces with their extensions; 40 and Fig. 7 shows an end view of the assembled parts.

The parts 1^a and 1^b shown at Fig. 1 are made up of brass or some other non-magnetic material and are placed on each side of the pole pieces 9 and 10 Figs. 5 and 7. Projections 16 fit into and are riveted fast to the pole pieces. A detail of the holes is shown in the pole piece Fig. 6 at 18. Projections 15 are for receiving torsional

50 springs 2, the holes 17 being square in order to make a snug fit for riveting the projections 15 after assembly. 3 in Fig. 2 is one of the armatures which fits into the hole 19 of the spring 2 and may be soldered or otherwise fixed thereto rigid at the central point of the armature. Fig. 3 shows the

spring, the armature and connecting rod assembled in sub-assembly. The rod 4 extends to the diaphragm or other devices desired for operating. Fig. 4 shows a schematic drawing of the double armature with their rods 4^a and 4^b joined to a third rod 5 and attached at 6 by soldering or otherwise, to the diaphragm 7 with its washer 8 for supporting said diaphragm. The 60 springs 2^a and 2^b in Fig. 4 may be of different thickness of metal in order to give them unlike periodicities. By having two armatures of different periodicities and a diaphragm with an entirely separated periodicity, the resultant period is a very much damped oscillation, and may be said to have 65 no period, or aperiodic in character.

Fig. 5 shows two permanent magnets 11 and 12 and a theoretical view of the magnetic and electrical circuits. Four windings 13 constitute the electro-magnets. Said electro-magnets may be wound on spools or bobbins as shown at 14 Fig. 7, one being placed on either side of the 70 springs 2^a and 2^b Fig. 5. The pole-piece extensions 9^a, 9^d, 10^a, 10^d are integral with their respective pole pieces and 9^b, 9^c, 10^b, 10^c are riveted to their respective pole-pieces 9 and 10 shown in Fig. 5 and Fig. 7, and are 75 directly opposite each other. The clearance between the extensions and the armatures is governed by the height of the spacers 1^a and 1^b Fig. 7. When an electrical impulse is passed through the windings 13 Fig. 5, the two armatures are energized and have like poles in the center and like poles at each end. This construction produces consequent poles. They are attracted in the same direction as indicated 80 by the arrows in the drawing. A reversal of current will cause a reversal in direction of the movement of the armatures. The armatures are fulcrumed at 2^a and 2^b Fig. 5. No adjustment is necessary as the armatures are held in alignment with respect to 85 each other by the diaphragm which allows of wide space between the armatures and their respective pole-piece extensions.

Fig. 6 at a, b, c, and d are shown the pole-piece extensions of one pole-piece. Extensions b and c may be blanked out and riveted to the pole-piece 9 which is bent to form an extension at each end thereof.

Having thus described my invention, what is claimed is:

1. An electro-magnetic device comprising

- a magnet having pole-pieces, said pole-pieces, having two pairs of extensions each of said extensions projecting toward and spaced directly opposite each other, two 5 separate moveable armatures, a separate flexible torsional mounting for each armature and means for holding said armatures in alignment with each other, and for spacing said armatures between said pole-pieces.
- 10 2. An electro-mechanical transforming device including pole pieces, a plurality of torsionally mounted movable armatures operatively related to said pole pieces, and means for combining the movements of said 15 armatures.
3. An electro-mechanical transforming device including pole pieces, a plurality of torsionally mounted armatures having free ends operatively related to said pole pieces 20 combined with means for aligning said armatures in spaced relation with said pole pieces.
4. An electro-mechanical transforming device including a plurality of movable ful- 25 crumed armatures, a diaphragm, a rod attached to said diaphragm, and means for operatively connecting said armatures to said rod.
5. An electro-mechanical transforming device including a diaphragm, pole pieces, a plurality of armatures torsionally mounted and arranged to operate between said pole pieces, and means for connecting said dia- 30 phragm to said armatures.
- 35 6. An electro-mechanical transforming device including a plurality of torsionally mounted armatures, and a plurality of pole pieces combined with means for aligning said armatures in spaced relation to said 40 pole pieces.
- 45 7. An electro-mechanical transforming device including pole pieces having a plurality of extensions, and a plurality of flexibly mounted armatures having unlike periodicities arranged in spaced relation to said extensions.
- 50 8. An electro-mechanical transforming device including flexibly mounted armatures having unlike periodicities, a diaphragm, and means including said armatures for actuating said diaphragm.
- 55 9. An electro-mechanical transforming device including movable armatures having unlike natural periodicities, pole pieces, and means for spacing said armatures relative to said pole pieces.
- 60 10. An electro-mechanical transforming device including a plurality of armatures, a plurality of torsional mountings for said armatures, a plurality of pole pieces arranged adjacent to said armatures a plurality of connecting means for said armatures, and means for actuating said armatures.
- 65 11. An electro-mechanical transforming device having a magnet including electro- magnets within the field of said magnet, said electro-magnets arranged to produce consequent poles, a plurality of movable members magnetically energized by said electro-magnets, and means combined with said electro-magnets and said movable members for producing mechanical vibrations. 70
12. An electro-mechanical transforming device including oppositely-disposed pole pieces each having four terminals, aligned bobbins disposed between said pole pieces, windings on said bobbins arranged to produce a consequent pole, and armature members extending through said bobbins. 75
13. An electro-mechanical transforming device including a magnet, pole pieces for said magnet, a plurality of extensions for said pole pieces, electro-magnets arranged between said pole pieces and extensions, and armatures extending through said electro-magnets, said electro-magnets being so arranged as to produce consequent poles in 80 said armature.
14. An electro-mechanical transforming device including electro-magnets, pole pieces and armatures, said electro-magnets being so disposed relatively to said armatures as to produce consequent poles in said armatures, said pole pieces being so disposed relatively to said armatures as to cause said pole pieces to attract and repel parts of said armatures when said electro-magnets are energized. 85
15. An electro-mechanical transforming device including a magnet, pole pieces for said magnet, a diaphragm, electro-magnets, a plurality of armatures adapted to be attached to said diaphragm by connecting rods extending through one of said pole pieces, a pair of spacing members adapted to receive said pole pieces, a pair of torsional spring mountings adapted to receive said armatures and said spacing members, and means for supplying an electric current to said electro-magnets for energizing said armatures producing a consequent pole at a point midway between said armatures. 90 100
16. An electro-mechanical transforming device including electro-magnets, pole pieces, a plurality of armatures arranged co-exten- 105 sively with said electro-magnets, torsional springs for holding said armatures in opera- 110 tive spaced relation to said pole pieces, and said electro-magnets adapted to produce consequent poles in said armatures. 115
17. An energy translator comprising a diaphragm, an electro-magnet, several armatures, spring means for suspending each of said armatures, each spring suspended 120 armature having its own natural period of free vibration and lying within the field of the electro-magnets, and means for connecting said armatures to said diaphragm. 125
18. An energy translator comprising a diaphragm, a magnet, several armatures, 130

each of said armatures within the field of said magnet, a coil of wire about each of said armatures, means for connecting said coils of wire in non-inductive relation to each other.

5 each other, and a connecting rod from each armature to said diaphragm.

19. An electro-magnetic device comprising a magnet, several armatures within the

field of said magnet, and a coil of wire about each armature, said coils being connected in non-inductive relation to each other. 10

In witness whereof, I hereunto subscribe my name this 14th day of July, A. D. 1925.

HENRY MERLE WILLIAMSON.
